UNITED STATES PATENT OFFICE.

ROBERT S. GAMBRELL, OF HONEA PATH, SOUTH CAROLINA.

PICKER-HEAD HOLDER.

1,426,175.

Specification of Letters Patent. Patented Aug. 15, 1922.

Application filed September 6, 1921. Serial No. 498,739.

To all whom it may concern:

Be it known that I, ROBERT S. GAMBRELL, a citizen of the United States, residing at Honea Path, in the county of Anderson and 5 State of South Carolina, have invented new and useful Improvements in Picker-Head Holders, of which the following is a specification.

This invention comprehends the provision 10 of a novel construction of means for associating a picker head with the picker stick of a loom, without the use of screws or other analogous fastening elements which weaken the picker stick, frequently causing the latter to break.

More specifically stated, the invention provides a holder of the above mentioned character which not only retains the picker head in effective engagement with the picker 20 stick, but also serves to brace and strengthen the latter.

The nature and advantages of the invention will be better understood when the following detailed description is read in connection with the accompanying drawing, 25 the invention residing in the construction, combination and arrangement of parts as claimed.

In the drawing forming part of the application like numerals of reference indicate similar parts in the several views, and wherein—

Figure 1 is a view in elevation showing the manner of associating the picker head 35 with the picker stick in accordance with the present invention.

Figure 2 is a sectional view taken on line 2—2 of Figure 1.

Figure 3 is a similar view taken on line 40 3—3 of Figure 1.

Figure 4 is a detail view of the holder.

Referring to the drawing in detail, 10 indicates a picker stick, the picker head being indicated at 11.

45 The holder forming the subject matter of

the present invention is preferably constructed from suitable metal, and is of substantially U-shaped configuration, being designed to straddle the stick 10, as illustrated in Figure 1. The holder is indicated at 12, 50 and may vary in size without departing from the spirit of the invention. The limbs 13 of the holder are inset from the cross member 14 to provide flanges 15 which affords the holder maximum strength and 55 rigidity. Obviously, when the holder is associated with the stick 10 it reinforces and braces the latter. The limbs 13 of the holder are held in face to face contact with the adjacent sides of the stick 10 through the 60 instrumentality of a sliding clamp 16, which is provided with a set screw 17.

In practice, the holder is slid through the head 11, after which the holder is positioned upon the stick 10, as shown in Figure 1. 65 The clamp 16 is then moved over the free ends of the limbs 13, bringing the latter into contact with the stick 10, and the parts held fixed relatively by means of the set screw 17.

While it is believed that from the foregoing description the nature and advantages of the invention will be readily understood, I desire to have it known that I do not limit myself to what is herein shown and 75 described, and that such changes may be resorted to as fall within the scope of the appended claim.

Having thus described the invention, what is claimed as new, is—

A picker head holder comprising a member including spaced limbs and a cross piece connecting the limbs at one end thereof, and said limbs being inset with relation to the cross piece to form inwardly directed flanges 85 to reinforce and strengthen said holder as and for the purpose specified.

In testimony whereof I affix my signature.

ROBERT S. GAMBRELL
